PRESS WITH DUAL SLIDING TABLE

Howard F. MacMillin, Mount Gilead, Ohio, assignor to The Hydraulic Press Corp., Inc., Wilmington, Del., a corporation of Delaware

Application July 21, 1937, Serial No. 154,854

6 Claims. (Cl. 100—71)

This invention relates to presses, and in particular, to hydraulic presses including arrangements having movable dies which can be moved into and out of pressing position.

One object of this invention is to provide a press having two or more tables or work-holders, arranged to move in and out of the press alternately so that a pressing operation may be performed on one table or portion of a table while another table or portion of a table is out of the press for the purpose of loading or unloading.

Another object is to provide a press having a pair of relatively movable work table units, each unit having at least two work-holding locations, the two units being movable alternately into and out of the press so that one pair of work-holding locations is in pressing position while the other pair of work-holding locations is outside the press so that workpieces may be unloaded from or loaded onto the work-holding locations.

Another object is to provide a press having dual movable tables as described above, wherein the means for moving the tables is synchronized with the means for moving the press platen or plunger so that the tables are moved only when the press platen is out of its pressing position.

Another object is to provide a press having relatively movable tables, as described above, wherein an electrical control system controls the action of the main plunger and also controls the action of auxiliary plungers for moving the work tables in and out.

Another object is to provide a press having a plurality of relatively movable work tables with hydraulic plungers for moving the work tables into and out of pressing position, together with an electrical control system synchronizing the moving of the tables with the moving of the main plunger or platen so that the work tables are moved into or out of pressing position only when the platen is out of its pressing position.

Another object is to provide a press having a member movable by a hydraulic piston, which has a stroke-cushioning arrangement associated therewith for cushioning the movement of the piston at one or both ends of its stroke.

Another object is to provide a press having relatively movable work tables operated by hydraulic motors, controlled by an electrical system so arranged that the electrical control system is energized to operate the pressing plunger solely when the tables are in their proper positions beneath the press platen.

Another object is to provide such a control system, wherein the operation of the main pressing

plunger is synchronized with the operation of the hydraulic motors for shifting the work tables in such a manner that the press may be operated manually by controlling the valves by hand, or 5 semi-automatically, wherein the press executes a complete working and return stroke and then comes to a halt, or fully automatically, wherein the press executes an indefinite number of working and return strokes before it is halted by the 10 operator.

Another object is to provide an apparatus for forming articles between forms, wherein the unpressed article is placed in a form in position for pressing and is pressed while another unpressed 15 workpiece is placed in an adjacent form, after which the pressed workpiece is moved out of pressing position while the second unpressed workpiece is moved into pressing position, preferably in response to the cessation of the pressing.

20 In the drawings:

Figure 1 is a front elevation of one embodiment of the press of this invention.

Figure 2 is a side elevation of the press shown in Figure 1.

25 Figure 3 is an enlarged central vertical section through a conventional type of control valve for the press shown in Figures 1 and 2.

Figure 4 is a vertical section through one of the work tables and its associated hydraulic motor, taken along the line 4—4 in Figure 5, and showing the piston cushioning arrangement according to the invention.

30 Figure 5 is a front elevation of the structure shown in Figure 4.

35 Figure 6 is a diagrammatic view showing the positions of the work tables and the limit switches when the tables are in one pressing position.

Figure 7 is a view, similar to Figure 6, but showing the tables in their opposite or shifted 40 positions.

Figure 8 is a diagrammatic view showing the hydraulic circuit for actuating the main or pressing plunger.

45 Figure 9 is a diagrammatic view showing the hydraulic circuit for actuating the table-moving cylinders.

Figure 10 is an electrical wiring diagram, showing the connections of the various electrical apparatus for controlling the motions of the press and work table motors.

50 Figure 11 is a simplified wiring diagram of the circuit shown in Figure 10.

General arrangement

In general, the press of this invention consists

of a pressing platen associated with a plurality of tables which are movable into and out of the pressing position, in such a manner that at least one table is beneath the pressing platen when its associated table is outside of the press for loading or unloading purposes. The embodiment shown in the drawings includes a pair of slides having places for two dies on each slide, the two slides being moved by double-acting hydraulic motors controlled by a valve through cross connections in such a manner that one of the tables is moved in one direction while the other table is moved in the opposite direction.

An electrical control system is provided for shifting the valve so as to control the movement of the tables, and also to synchronize the movement of the tables with the motion of the pressing plunger. With the control circuit of this invention, the pressing plunger cannot complete a pressing stroke until one set of dies is in position under the platen and the other set of dies is completely outside the press. The slides or tables are moved by hydraulic motors having a special cushioning arrangement for cushioning the pistons at the opposite ends of their strokes.

Press construction

Referring to the drawings in detail, Figure 1 shows a front elevation of a press having a bed or base member 10 with side members 11 rising therefrom, and a top member 12 thereover, the whole being interconnected by strain rods 13 and nuts 14 threaded upon the ends thereof. Mounted upon the top member 12 is a surge tank 15 having means for storing the oil or other working fluid used in the press. The top member 12 also contains a main cylinder 16 (Figure 8) having a main plunger 17 therein and ports 18 and 19 communicating by conduits 20 and 21 with a control valve 22.

The control valve 22 shown in Figure 3 is of a conventional four-way type well known to those skilled in the art, and includes a casing 23 having a bore 24 with end chambers 25 and 26, a middle chamber 27 and intermediate chambers 28 and 29. The end chambers 25 and 26 are interconnected by a passageway 30 having a port 31 and conduit 32 leading therefrom. The middle chamber 27 has a port 33 having a conduit 34 leading therefrom. The intermediate chambers 28 and 29 have ports 35 and 36, from which the conduits 20 and 21 lead to the main cylinder 16 at its opposite ends. End plates 37 and packings 38 prevent escape of fluid from the ends of the casing 23. Reciprocably mounted in the valve bore 24 is a valve member 39, having spaced heads 40 and 41 thereon. A spring 42 urges the valve member 39 in one direction, whereas a solenoid 43, connected thereto by the links and levers described below, when energized, urges it in the opposite direction. The spring 42 is retained in position by a hollow cap 22a secured to the casing 23. The spring 42 is engaged by a collar 44, secured to the valve member 39.

The conduit 32 leads from the passageway 30 and port 31 to the fluid tank 15. The conduit 34, however, leads to the main pump 46, from which the suction line 47 leads to the tank 15. A relief valve 48 is installed in the pressure line 34 from the pump 46, and has an outlet line 49 connected to the exhaust line 32. The solenoid 43 is connected to the valve member 39 by means of a train of links and levers, including the link 50 interconnecting the solenoid armature 51 with one end of the lever 52. The latter is pivoted

on the shaft 53 which carries an arm 54 having a link 55 connecting it to the arm 56 on the shaft 57, the latter also carrying an arm 58 having the link 59 connecting it to the valve rod 39. The other end of the lever 52 is provided with a yoke portion 60, engaged by a collar 61 upon the control rod 62 of the press (Figure 2). The control rod 62 is mounted for vertical sliding movement in the projections 63 and 64 on the top and bottom members 12 and 10, respectively. The lower end of the control rod 62 carries a collar 65, engaged by a yoke 66 upon the end of an arm 67 pivotally mounted upon the shaft 68 and having an operating handle 69 secured thereto for manually operating the valve 22.

Connected to the main plunger 17 is a platen 70 having a plurality of dies 71 and 72, arranged side-by-side and cooperating with mating dies 73 and 74 upon sliding tables 75 and 76. Extending downwardly from each end of each of the tables 75 and 76 is an end member 77 having an aperture 78, through which passes the threaded end 79 of an auxiliary piston rod 80 and secured in position by the nuts 81 and 82 thereon. The tables 75 and 76 and the table supports 83 and 84 are provided with cooperating guiding ridges and grooves 85 and 86, respectively. The grooves 86 adjoin wear plates 87, secured to the tables 75 and 76 (Figure 4). The table supports 83 and 84 are provided with cylinder bores 88 having outlet ports 89 and 90 and end members 91 with packings 92 compressed by glands 93. The piston rod 80 is provided with adjustable collars 94 and 95, secured thereto by the set screws 96. The piston rod 80 is also provided with a piston head 97 reciprocable within the bore 98 of a sleeve 99, having end closures 100 with restricted fluid ports 101 therein. This construction provides a cushioning action of the piston head 97 as it nears the opposite ends of its stroke. Under these conditions, one of the end closures 100 collides with one of the end members 91. The piston head 97, however, continues to move at a reduced rate, controlled by the rapidity of escape of the fluid through the ports 101. The table supports 83 and 84 are mounted upon the bed 10 of the press. Pressure gauges 102 and 103 are provided on the top member 12 for indicating the pressures obtained in the hydraulic circuits.

The hydraulic circuit for actuating the piston rods 80 and tables 75 and 76 (Figure 9) consists of the cylinders 88. Connected to these tables are the four-way valve 104, similar in construction and operation to the four-way valve 22 already described, the relief valve 105, which is likewise similar to the relief valve 48, and the pump 106 for supplying pressure fluid to the cylinders 88. The cylinders 88 for the tables 75 and 76 are cross-connected with the four-way valve 104 in such a manner that when the pressure fluid is supplied to one end of one cylinder it is simultaneously supplied to the opposite end of the other cylinder, thereby causing the piston rods 80 to travel simultaneously in opposite directions.

To this end the conduit 107 runs from the port 90, at the rearward end of the left-hand cylinder 88, to the four-way valve 104, and a branch line 108 therefrom runs to the forward port 89 of the right-hand hydraulic cylinder 88. Similarly, a line 109 runs from the forward port 89 of the left-hand hydraulic cylinder 88 to the four-way valve 104, and has a branch line 110 running to the rearward port 90 of the right-hand hydraulic cylinder 88. From the four-way valve 104 the

line 111, containing the relief valve 105, runs to the pump 106, and beyond this the suction line 112 runs to the surge tank 15. From the four-way valve 104 the discharge line 113 likewise runs to the surge tank 15, and is joined by the discharge line 114 from the relief valve 105.

The valve member 115 of the four-way valve 104 is urged in one direction by the coil spring 116 having the collar 117 secured thereto, and in the opposite direction by the solenoid 118 when the latter is energized. The four-way valve 104 is operated from the armature 119 of the solenoid 118 (Figure 2) by a link 120 connected to one arm of the bell-crank 121, the opposite arm of which is connected to the valve member 115. The platen 70 is provided with a projecting portion 122, which is adapted to engage a collar 123 adjustably mounted upon the control rod 62. The control rod 62 also carries an adjustable collar 124 for operating a limit switch 145, as hereinafter described. Mounted on the forward side of the press is a switch box 125, containing certain switches for controlling the press. A second switch box 126 is mounted upon the rearward side of the press. An indicating light 127 burns when the circuit is energized.

Electrical circuit

The electrical circuit (Figures 10 and 11) includes a three-point forward push button switch 128, a two-point forward push button switch 129, a pair of foot-operated emergency reverse switches 130 and 131, a two-way hand selector switch 132 and a two-way automatic selector switch 133; also four limit switches 141, 142, 143 and 144 mounted upon the front and rear of the press bed 10 and actuated by the tables 75 and 76 when these reach their opposite extreme positions (Figures 6, 7 and 10). A fifth limit switch 145 is operated by the collar 124 when the projection or platen arm 122 raises the collar 123 and control rod 62 at the end of the return stroke of the platen 70. A normally open pressure switch 146 is closed when the fluid within its cylinder 147 reaches a predetermined value. This pressure switch cylinder 147 is connected to the main cylinder 16 and operated when the pressure within the main cylinder 16 reaches the amount for which the pressure switch 146 is set.

The electrical circuit also contains a two-blade control relay 151, both of its blades being normally open, a single-blade control relay 152 with a normally open blade, and a two-blade control relay 153, the left-hand blade being normally closed and the right-hand blade normally open. A single-blade ratchet relay 154 of a conventional type having a normally open blade cooperates with these relays to control the energization of the normally open contactor switches 155 and 156. A resistance 157 is included in the circuit of the indicating light (Figure 11).

Operation

For convenience, let it be assumed that the tables 75 and 76 are each provided with a pair of work locations, respectively designated 158 and 159, 160 and 161 (Figures 6 and 7). If the press is arranged for embossing, this construction enables one pair of workpieces to be pressed while the other pair is being loaded. Each press employs two operators, one at the front of the machine and the other at the rear, the separate forward switches 128 and 129 being provided for safety purposes; likewise, the foot reverse switches 130 and 131. Since the switches 128 and 129 are

in series, the press cannot be operated electrically until both operators of the press depress their respective switches.

When the press is ready to be started, one operator adjusts the selector switches 132 and 133 according to the type of operation desired. If the selector switch 132 is set at the "hand" position, all control circuits are deenergized so that the electrical system is completely out of operation. Under these conditions the press can be operated solely by the hand lever 69. The electrical system permits the press to be operated automatically, in a semi-automatic or a full-automatic manner. In semi-automatic operation the press platen descends, performs a pressing stroke, returns to its starting position and halts. It is then necessary for the operator to operate the forward switch in order to perform another pressing operation. In full automatic operation, however, the press platen performs an indefinite number of pressing and return strokes without halting, until the press is stopped by the operator, such as by depressing one of the foot switches 130 or 131, or by throwing the usual line switch.

For full automatic operation the operator sets the upper selector switch 132 to the automatic position, and the lower selector switch 133 to the full automatic position. Both operators then depress the forward switches 128 and 129. The coil of the control relay 151 is then energized from the power line 162 by way of the hand-automatic selector switch 132, the reverse switches 131 and 130, the forward push button switches 129 and 128, the control relay coil 151 and the power line 163. When the push buttons 128 and 129 are released, the coil of the control relay 151 is held in an energized position by a holding circuit bridging these switches through the now closed left-hand switch blade of the relay 151.

With the closing of the right-hand switch blade of the control relay 151 the contactor switch 155 becomes energized from the power line 162 by way of the now closed right-hand switch blade 45 of the control relay 151, the normally open but now closed limit switches 141 and 144, which are now closed by their respective tables, the full automatic pole of the selector switch 133, the coil of the contactor switch 155, the left-hand normally closed switch blade of the control relay 153 to the power line 163. When the blades of the contactor switch 155 close, upon the energization thereof, the winding of the solenoid 43 is energized from the power lines 162 and 163. This shifts the valve member 39 of the four-way valve 22, causing pressure fluid to pass from the pressure line 34 to the line 20, and permitting fluid to be withdrawn through the lines 21 and 32. When thus supplied with pressure fluid the main plunger 17 and platen 70 start downward and perform a pressing stroke. When the pressure rises to a predetermined value the pressure fluid within the main cylinder circuit closes the normally open pressure switch 147. This action energizes the coil of the control relay 153 from the power line 162 by way of the pressure switch 146, the coil of the control relay 153 to the power line 163.

As the control relay 153 closes, it opens its left-hand blade and closes its right-hand blade. A subsequent drop of pressure in the main cylinder circuit, however, while releasing the pressure switch 146 so that it assumes its normally open position, does not disturb the energization of the coil of the control relay 153 because this is held

energized by a holding circuit bridging the pressure switch 146 through the right-hand switch blade, and through the contacts of the normally open but now closed table limit switches 141 and 144. The energization of the control relay 153 opens its left-hand switch blade and thereby de-energizes the coil of the contactor switch 155, deenergizing the solenoid 43 and permitting the spring 42 to shift the four-way valve 22 and cause pressure fluid to be admitted to the line 21, while permitting the line 20 to become a discharge line connected to the line 32. The main plunger 17 accordingly reverses and starts to move upward on its return stroke.

As the main plunger reaches the top of its return stroke the platen arm 122 lifts the collar 123 and control rod 62, thereby causing the collar 124 to close the normally open limit switch 145. This action energizes the coil of the ratchet relay 154, which energizes or deenergizes the coil of the contactor switch 156, depending upon the position of the ratchet contact of the relay. The energization of the contactor switch 156 causes its normally open blades to close, thereby energizing the solenoid 118 and shifting the four-way valve 104. Accordingly, pressure fluid is admitted oppositely to the cylinders operating the tables 75 and 76 so that these tables move simultaneously in opposite directions. The blanks which the operators have placed upon the exposed work locations thus move into the press, and the other two locations move out with the finished workpieces. The operators remove the finished workpieces and replace them with other blanks.

The shifting of the tables 75 and 76 to their opposite positions releases and opens the table limit switches 141 and 144, and at the same time engages and closes the limit switches 142 and 143. While the tables are shifting, however, the coil of the control relay 153 becomes deenergized when the previously described holding circuit is broken, thereby closing its normally closed left-hand switch blade and placing the circuit of the coil of the contactor switch 155 in readiness for re-energization. This reenergization occurs as soon as the limit switches 142 and 143 close through the same circuit as previously described in connection with limit switches 141 and 144. The tables 75 and 76 are now in their reverse positions, and the solenoid 43 is again energized, shifting the control valve 22 and causing the main plunger 17 and platen 70 to start downward, executing another forward stroke. In this manner the press executes an indefinite number of working strokes, and the tables 75 and 76 shift their positions automatically between pressing strokes. The repeated cycles of operations continue until the press is halted by the operator, either by depressing the emergency reverse switch 130 or 131, or by throwing the usual line switch.

For semi-automatic operation the operator leaves the selector switch 132 at the automatic position, but shifts the selector switch 133 to the semi-automatic position. The forward push button switches 128 and 129 are now depressed by the operators, thereby reenergizing the coil of the control relay 151, in the manner previously described. The coil of the control relay 152 is also energized by a circuit completed at the middle contact of the three-point forward push button switch 128, it being in parallel with the coil of the contactor switch 151 under these conditions. As the control relay 152 has but a single blade, however, it lacks a holding circuit, hence, is imme-

diately deenergized by the opening of any of the push button switches. The coil of the contactor switch 155 is now energized from the power line 162, through the normally open but now closed right-hand switch blade of the control relay 151, the normally open but now closed limit switches 141 and 144 (or 142 and 143), the normally open but now closed contacts of the control relay 152, the semi-automatic pole and switch blade of the selector switch 133, the coil of the contactor switch 155, the normally closed switch blade of the control relay 153 to the power line 163. The coil of the contactor switch 155 is held in energization by a holding circuit through the left-hand switch blade thereof bridging the normally open contacts of the control relay 152, so that the energization of the solenoid 43 continues even when the control relay 152 is deenergized.

When the main plunger 17 performs its pressing stroke, the pressure within the hydraulic circuit closes the normally open pressure switch 146, thereby energizing the coil of the control relay 153, as before, this energization being held through a holding circuit including the right-hand switch blade of the control relay 153. The opening of the normally closed left-hand switch blade thereof deenergizes the contactor switch 155 and consequently deenergizes the solenoid 43. The spring 42 then shifts the valve member 39, reversing the flow of fluid to the main cylinder 16, thereby reversing the travel of the main plunger 17 and causing a return stroke to occur, as before. As the main plunger 17 reaches the top of its return stroke, the platen arm 122 again lifts the control rod 62 and closes the normally open limit switch 145, as before, thereby reenergizing the coil of the ratchet relay 154 and again energizing or deenergizing the contactor switch 156 and solenoid 118, depending upon the positions of the ratchet relay contacts.

The tables 75 and 76 again shift their positions, releasing the limit switches 141 and 144 and engaging the limit switches 142 and 143. The consequent opening of the normally open limit switches 141 and 144 again deenergizes the coil of the control relay 153, but the energization of the coil of the contactor switch 155 is not now completed because the deenergization of the control relay 152 has now broken the circuit. The platen arm 122, therefore, moves the control valve 22 into its neutral position, by-passing the discharge of the pump 46 and causing the platen 70 to halt at the top of its return stroke.

It will be understood that I desire to comprehend within my invention such modifications as come within the scope of the claims and the invention.

Having thus fully described my invention, what I claim as new and desire to secure by Letters Patent, is:

1. In a work-holding device for presses, a support, a plurality of work-holder pairs movably mounted on said support, a hydraulic motor operatively connected to each work-holder pair, a source of pressure fluid, hydraulic connections for connecting said source to said motors, and means for distributing said pressure fluid to said motors and said work-holder pairs so as to cause said motors to move simultaneously in opposite directions.

2. In a work-holding device for presses, a support, a plurality of work-holders movably mounted on said support, a hydraulic motor operatively connected to each work-holder, con-

duits interconnecting one end of one motor with the opposite end of the other motor, a source of pressure fluid connected to said conduits, and means for regulating the flow of fluid from said source to said conduits.

3. In a press, a pressing platen, means for moving said platen, a support, a plurality of work-holder pairs arranged in a single horizontal plane, the work-holders of each pair being positively interconnected and in alignment with each other, and each pair having a hydraulic motor associated therewith, means hydraulically interconnecting said motors for effecting synchronous movement thereof in opposite directions, and means responsive to the arrival of said work-holders at predetermined positions for initiating the action of said platen-moving means.

4. In a press, a pressing platen, a motor therefor, a support, a plurality of work-holders arranged in a single horizontal plane and movably mounted on said support, hydraulic means operatively interconnecting said work-holders for effecting simultaneous movement thereof in opposite directions so as to bring two work-holders into pressing position while at the same time bringing two other work-holders into unloading position, and means responsive to the arrival of said platen at a predetermined position for actuating said work-holder-moving means to move said work-holders into position for pressing by said platen.

5. In a press, a pressing platen, a motor there-

for, a support, a plurality of work-holder pairs arranged in a single horizontal plane and movably mounted on said support, hydraulically operable plungers respectively connected with said work-holder pairs and hydraulically interconnected for moving said work-holder pairs simultaneously in opposite directions so as to bring two work-holders into pressing position while at the same time bringing two other work-holders into unloading position, means responsive to the arrival of said platen at a predetermined position for actuating said work-holder operating plungers to move two of said work-holders into position for pressing by said platen, and means responsive to the arrival of said work-holders at predetermined positions for energizing said platen motor.

6. In a work-holding device for presses, two pairs of work-holders movably mounted in one and the same plane, the work-holders of each pair being positively connected with each other, two double-acting fluid operable plungers operatively connected with said pairs respectively, conduit means interconnecting one side of one plunger with the opposite side of the other plunger, a fluid source adapted to supply pressure fluid to said conduit for actuating said plungers so as to move their respective work-holder pairs simultaneously and in opposite directions, and means for regulating the flow of fluid from said source to said conduit.

HOWARD F. MACMILLIN.
